A. C. OLANDER,
RESERVE STORAGE VALVE,
APPLICATION FILED OCT. 11, 1917.

1,276,102.

Patented Aug. 20, 1918.

By *Geo. P. Kimmel*
Attorney

UNITED STATES PATENT OFFICE.

ALDEN C. OLANDER, OF BILLINGS, MONTANA.

RESERVE-STORAGE VALVE.

1,276,102.

Specification of Letters Patent. Patented Aug. 20, 1918.

Application filed October 11, 1917. Serial No. 195,948.

To all whom it may concern:

Be it known that I, ALDEN C. OLANDER, a citizen of the United States, residing at Billings, in the county of Yellowstone and State 5 of Montana, have invented certain new and useful Improvements in Reserve - Storage Valves, of which the following is a specification.

This invention relates to valves and has 10 more especial reference to a reserve storage valve for use in connection with fluid fuel tanks.

The invention has for its principal object 15 to provide a valve which can be readily applied over the outlet means of a fluid fuel storage tank with but slight alteration thereto, whereby a quantity of fuel will be always held in reserve in the tank and when the occasion so requires, may be allowed to flow 20 therefrom, thus enabling the engine or other apparatus receiving the fuel to continue to operate for a short period of time; the device, obviously, being especially desirable for use on motor driven vehicle fuel tanks, permitting 25 the vehicle to reach a supply station or the like whereupon the tank can be refilled.

Among other aims and objects of the invention may be recited, the provision of a 30 device of the character mentioned with a view to compactness, and in which the number of parts are few, the construction simple, the cost of production small, and efficiency and operation high.

The improvements in the details and arrangement of parts will be apparent from an 35 inspection of the accompanying drawings, in connection with the specific description hereinafter contained, and wherein the preferred embodiment of the invention is disclosed for the purpose of imparting a full understanding of the same.

In the drawings:

Figure 1 is a vertical section through a 40 fuel tank provided with the improved valve, and

Fig. 2 is a vertical section through a slightly modified form of valve.

Having more particular reference to the 45 drawings and in connection with which like reference characters will refer to corresponding parts throughout the several views, 1 represents a fluid fuel storage tank having a screw threaded outlet opening 2 formed 50 in the bottom thereof and a similarly thread-

ed filling opening 3 formed in the top thereof.

Arranged over the outlet opening 2 is a vertically disposed cylindrical valve cage 4, the upper end of which is opened for a purpose which will be subsequently apparent. A valve 5 comprising a hollow cylindrical body is slidably received in the cage 4 and has the lower portion thereof ground and shaped to permit seating of the same upon 60 the marginal edge of a bushing 6, the said bushing being screw threaded and turned into engagement with the outlet opening 2. In this connection, it is to be noted that the cylindrical valve 5 is of a length slightly 65 less than its cage 4 and has movement of the same with relation to the cage limited by means of a flange 7 formed upon the upper marginal edge of the said cage. A pin 8 is passed through the upper end of the 70 valve 5 and is engaged by the adjacent end of a contractile coiled spring 9, the lower end of which is engaged with a similar pin 10 passed through the upper end of the screw 75 threaded bushing 6. By so engaging the 80 valve 5 it will be readily understood that the same will be normally maintained seated upon the bushing 6 and as a consequence, will permit the flow of fuel by the same, thereby maintaining a predetermined 85 reserve quantity of fuel in the tank for use in emergency.

A cap 11 is turned into engagement with the screw threaded opening 3 and is provided with a concentric opening through 90 which a cord 12 is passed downwardly into engagement with the cross pin 8. To prevent displacement of the cord 12 a knob 13 may be and preferably is arranged upon its free extremity which as will be noted, is 95 positioned exteriorly of the tank 1. A spindle 14 is carried by the cap 11 and is adapted to have the exterior portion of the cord 12 coiled thereabout whereby the same will be maintained in a position convenient 100 to the user and also to hinder removal of the cap 11 until the cord 12 has been disengaged therefrom and the valve 5 permitted to close. A spring clip 15 is also arranged upon the cap 11 and serves as additional 105 means for locking the cord and hence, the valve 5 in an open or partially opened position to permit the passage of the entire quantity of fuel from the tank 1.

In Fig. 2 I have shown a slightly 110

modified form of valve, the same being particularly adaptable for use on tanks containing heavy liquid fuel. In this particular embodiment, the valve cage 4' is provided with diametrically disposed vertical slots 16 through which arms 17 carried upon the upper end of the valve 5 are received. Other arms 18 are arranged at diametrically opposite points upon the bushing 6 and serve as means for receiving certain of the ends of contractile coiled springs 19, the remaining ends of the said springs being secured to the arms 17 and serving as means for normally maintaining the valve 5 seated over the outlet opening of the fuel tank. By so arranging the springs, it will be understood that an unobstructed passage for the bulk of the fuel flowing from the tank is provided.

29 From the foregoing, it will be appreciated by workers skilled in the art that with my improved valve, a reserve quantity of fuel will be normally maintained in a fuel tank, thus enabling the device receiving the fuel to operate for a brief period of time subsequent to the discharge of the bulk of fuel therefrom. The device may be advantageously used upon the fuel tanks of motor driven vehicles wherein it frequently occurs

30 that the supply of fuel from the storage tank is exhausted before the operator notices the same. With my improved device, by pulling the cord 12 upwardly the valve will be raised from over the outlet opening in the tank, thus allowing the reserve quantity of fuel to flow by the same to the engine. The construction of the valve is such as to avoid the hindering of the passage of fuel through the same to the outlet conduit.

40 Manifestly, the construction shown is capable of considerable modification and such modification as is within the scope of my claims, I consider within the spirit of my invention.

I claim:—

45

1. In combination with a receptacle having an outlet opening therein, a cage over said opening, a hollow cylindrical valve slidably received in the cage, the upper end of said cage being flanged for limiting movement of said valve therein, and means engaged with the valve for normally maintaining the same over said outlet opening for reserving a predetermined quantity of fuel in said receptacle. 50

55

2. In combination with a receptacle, having an outlet opening therein, a cage over said opening, a hollow cylindrical valve slidably received in the cage, the upper end of said cage being bent to form a flange for limiting movement of the valve therein, spring means engaged with the valve for normally maintaining the same over said outlet opening for reserving a predetermined quantity of fuel in said receptacle, 60 and means connected to the valve and extending exteriorly of the receptacle for facilitating operation thereof. 65

70

3. In combination with a receptacle, having a filling and an outlet opening therein, 70 a valve cage arranged over said outlet opening, a hollow cylindrical valve slidable in said cage, the upper end of the cage being flanged to limit movement of the valve therein, spring means engaged with the valve for normally maintaining the same seated over said outlet opening for reserving a predetermined quantity of fuel in said receptacle, 75 a closure receivable in the filling opening, a cord passing through the closure into engagement with said valve, and means on the closure engageable with the cord for locking the same and maintaining the valve in adjusted position. 80

80

In testimony whereof I affix my signature 85 hereto.

ALDEN C. OLANDER.
